ATTORNEY

UNITED STATES PATENT OFFICE.

ADOLPH HERD, OF YOUNGSTOWN, OHIO.

GARMENT MARKER.

1,414,643.

Specification of Letters Patent. Patented May 2, 1922.

Application filed October 21, 1920. Serial No. 418,453.

To all whom it may concern:

Be it known that I, ADOLPH HERD, citizen of the United States, residing at Youngstown, in the county of Mahoning and State 5 of Ohio, have invented certain new and useful Improvements in Garment Markers, of which the following is a specification.

This invention relates to improvements in that type of tailoring appliances known as 10 "garment gages and markers," and commonly termed "skirt gages" or "skirt markers." One object of the invention is to provide a simple and practical form of marking device designed to be associated with any 15 suitable supporting means, to provide for accurately and expeditiously marking, or indicating the proper length of the skirt or garment.

Another object is to combine two features 20 which, while really independent of each other, may often be used alternately with great advantage to the operator.

I recognize, of course, the similarity in 25 many respects of this invention to the invention covered by United States Letters Patent No. 1,316,613 issued to me under date of September 23, 1919, and the purpose of the present application is to cover certain improvements which experience has convinced me are material and important.

Figure 1 is a side elevation partly in section; Figure 2 is a top plan view; and Figure 3 is a vertical longitudinal section on line 3—3 Figure 2.

Like reference characters designate corresponding parts throughout the various figures of the drawings.

The marking device proper, which constitutes the essential feature of the present invention, may be utilized in connection with any suitable form of support to make the complete working article. In the present instance, it is shown as being associated with the standard 1 supported by the ordinary 40 base 2.

Slidably mounted upon the standard 1 is the horizontal bar 4 provided with the clamping screw 5 to hold it in any desired position on the standard. One end of the 50 bar 4 is turned downwardly at substantially right angles at the point 6, thus forming what may be termed a supporting bracket 7, to which is attached, at substantially right angles thereto, the open guide-way 8, having 55 the side walls 9—9 and the bottom 10.

The bar 4 is provided, adjacent point 6,

with the slot 11 within which the trigger-lever 12 is pivoted upon the pin 13. Immediately below pin 13 is the pin 14 upon which is pivoted the lever or bar 15,— the upwardly 60 extending point 16 of which engages the notch 17 formed in the head of trigger-lever 12.

Slidably mounted within the guide-way 8 is the containing box 18, which is designed 65 to carry the powdered chalk or other similar ingredient used for marking the goods, and provided with the filling opening 19 which is closed by the cork or stopper 20.

Firmly attached to the rear end of the 70 containing box 18 is the short stem 21, provided with the notch or slot 22 for engagement with the lower end 23 of the lever 15. Mounted upon pin 14 is also the wire spring 23^a designed to actuate lever 15, when released from pressure under lever 12.

The outer or forward end of box 18 is provided with a plurality of orifices 24 through which the marking substance is ejected.

The bottom 10 of the guide-way 8 is provided at its outer end with a short longitudinal guide-slot 25, within which slides a depending lug 26 carried by the containing box 18, and provided with the key hole 27 85 for the key 28.

The opposite end of bar 4 is provided, adjacent the standard 1, with the bowl or receptacle 29, and beyond the bowl with the downwardly curved arm or member 30,— 90 the upper face 31 of the outer end of which is disposed in the same horizontal plane as the jet orifices or discharge holes 24 in box 18. This arm 30 also carries the finger-piece or grip element 32 to facilitate the holding 95 of the goods.

The operation of the device is as follows: The marker is first adjusted to the desired height on the standard where it is secured by the clamping screw 5. The device is then 100 placed in proper relation to the garment to be marked, and the operator presses the free end of lever 12 downwardly, drawing the box 18 rear-wardly in the guide-way 8. Upon sudden releasing of lever 12, spring 105 23^a, pressing against the lower end 23 of lever 15, will force box 18 outwardly in guide-way 8; and the sudden stopping of the same will cause a sufficient quantity of the marking substance to be ejected through the orifices 110 24 to produce the desired marking. Or, if it is desired to use the opposite end of the

marker, it may be placed in proper relation to the garment, after which the pins or chalk marks are placed, at the point indicated by the upper edge 31 of arm 30.

5. Experience has taught me that it is frequently convenient to use the two parts alternately, changing from one to the other as the situation or occasion may require, thus giving decided value to the dual or combination features of the device.

I claim:—

1. In a garment marker, in combination with a support and a guide-way carried thereby, a marking device comprising a powder carrying case slidably mounted in said guide-way and provided at its forward end with one or more jet orifices, and manually operated mechanism for imparting to said case a reciprocal motion in said guide-way.

2. In a garment marker, in combination with a support and a guide-way carried thereby, a marking device comprising a powder carrying case slidably mounted in said guide-way and provided at its forward end with one or more jet orifices; a trigger-lever pivoted in the support; a spring-actuated swinging lever also pivoted in the support,—said two levers having such interlocking engagement as to cause them to move conjunctively, and the latter being also connected with said powder carrying case.

3. In a garment marker, in combination with a support and a guide-way carried thereby, a marking device comprising a powder carrying case slidably mounted in said guide-way and provided at its forward end with one or more jet orifices and at its rear end with a rigidly attached stem; a trigger-lever pivoted in the support, one end of said lever constituting a finger-piece and the other end being provided with a substantially circular head having a concave section in its periphery; and a spring-actuated swinging lever also pivoted in the support, one end of said swinging lever engaging the concave section in the head of said trigger-lever, and the other end engaging the stem carried by said case.

4. In a garment marker, in combination with a support, a combination marking device comprising on one side of said support a guide-way carried thereby, a powder

carrying case slidably mounted in said guide-way and provided at its forward end with one or more jet orifices, and manually operated mechanism for imparting to said case a reciprocal motion in said guide-way; and on the opposite side of said support, a gage bar, the upper or marking edge of which occupies the same horizontal plane as said jet orifices.

5. In a garment marker, in combination with a support, a combination marking device comprising on one side of said support a guide-way carried thereby, a powder carrying case slidably mounted in said guide-way and provided at its forward end with one or more jet orifices; a trigger-lever pivoted in the support; and a spring-actuated swinging lever also pivoted in the support,—said two levers having such interlocking engagement as to cause them to move conjunctively, and the latter being also connected with said powder carrying case and on the opposite side of said support, a gage bar, the upper or marking edge of which occupies the same horizontal plane as said jet orifices.

6. In a garment marker, in combination with a support, a combination marking device comprising on one side of said support a guide-way carried thereby, a powder carrying case slidably mounted in said guide-way and provided at its forward end with one or more jet orifices, and at its rear end with a rigidly attached stem; a trigger-lever pivoted in the support, one end of said lever constituting a finger-piece, and the other end being provided with a substantially circular head, having a concave section in its periphery; and a spring-actuated swinging lever also pivoted in the support, one end of said swinging lever engaging the concave section in the head of said trigger-lever, and the other end engaging the stem carried by said case; and on the opposite side of said support, a gage bar, the upper or marking edge of which occupies the same horizontal plane as said jet orifices.

In testimony whereof I hereunto affix my signature in the presence of two witnesses.

ADOLPH HERD.
